WOVEN MESH FABRIC

Gunter H. Stern, St. Louis, Mo., assignor to Continental Textile Corporation of America, St. Louis, Mo.

Filed Sept. 16, 1970, Ser. No. 25,025

Term of patent 14 years

U.S. Cl. D92—1 Y Int. Cl. D5—05

FIG. 1.

FIG. 2.

FIG. 1 is a top plan view of a woven mesh fabric of indeterminate length showing my new design, approximately two-thirds of the width of the fabric (considered vertically of the figure) being omitted for convenience of illustration, the design being continuous to the opposite side, and the edge being reversely similar to the edge shown at the top of the figure.

FIG. 2 is an enlarged fragmentary view thereof.

I claim:

The ornamental design for a woven mesh fabric, as shown and described.
